UNITED STATES PATENT OFFICE.

HERBERT ROBINSON, OF HALIFAX, ENGLAND, ASSIGNOR TO JOSEPH WILD & CO., OF NEW YORK CITY.

DESIGN FOR A CARPET-PATTERN.

Specification forming part of Design No. 5,842, dated May 7, 1872.

Specification describing a new and original Design for Carpet, invented by HERBERT ROBINSON, of Halifax, in the county of York, England.

The accompanying photograph fully illustrates my new design.

This invention relates to a new design for the center-figure of a carpet, one of said figures being of octagonal form, with small hexagons in the alternate sides, and containing an ornamental quatrefoil, while the other figure is four-sided, with concave-beveled corners and semi-spherical projections at the sides and ends. A pair of vine branches with flowers embraces the latter figure, as shown.

I claim as my invention—

The design for a carpet, containing the ornamental figures, as shown.

HERBERT ROBINSON.
